FIG. II

UNITED STATES PATENT OFFICE.

HENRY WIEDERHOLD, OF PHILADELPHIA, PENNSYLVANIA, ASSIGNOR TO THE BARBER ASPHALT PAVING COMPANY, OF PHILADELPHIA, PENNSYLVANIA, A CORPORATION OF WEST VIRGINIA.

APPARATUS FOR APPLYING MASTIC TO WALLS.

1,228,353.

Specification of Letters Patent.

Patented May 29, 1917.

Application filed January 2, 1915. Serial No. 206.

To all whom it may concern:

Be it known that I, HENRY WIEDERHOLD, of Philadelphia, in the county of Philadelphia and State of Pennsylvania, have invented a certain new and useful Apparatus for Applying Mastic to Walls, whereof the following is a specification, reference being had to the accompanying drawings.

My invention relates to a temporary structure and supporting means, whereby I am able to apply a bituminous lining to a vertical or inclined concrete wall. The application of such a lining to concrete walls is useful, as for example where receptacles, such as reservoirs or tanks made of cement or concrete, are to be used to hold liquids which are corrosive in their nature, such as the acid liquids frequently used in metallurgical or other chemical processes.

20 The present application is not concerned with the composition of the bituminous lining. In general it is a mastic-like mixture, of a bituminous cementing material with a mineral aggregate. Such material has already been described by me in an application executed by me and filed simultaneously herewith, Serial Number 204. Such a bituminous mixture is quite fluid when hot, but at atmospheric temperatures sets to form 30 a hard bituminous substance suitable for lining surfaces as above described.

No particular difficulty is experienced in applying such a bituminous lining to a substantially horizontal surface of concrete; 35 but with inclined or vertical surfaces or walls, difficulty is experienced because the material as it cools passes too quickly from the liquid to the solid state to permit of its being applied with a trowel as are ordinary 40 mortars or other plastics.

According to my invention, in order to apply such lining to a vertical or inclined wall, lathing is first attached to the wall, and a temporary structure with a limiting 45 surface erected parallel to the wall at a distance corresponding to the thickness of the lining which it is proposed to apply. The lining is then poured, while hot and fluid, into the space between the wall and the 50 limiting surface and allowed to cool and set.

The object of my invention is to provide a suitable temporary limiting structure which will successfully prevent the escape of the liquid material until it has cooled and

set; and which may be both easily erected 55 and removed and capable of repeated use.

It is obvious that as the liquid is poured in, the pressure at the bottom will depend on, and increase in direct proportion to the height of the liquid in the mold. It is also 60 obvious that as the pressure increases, the more the liquid will be forced through the joints, and the tighter the joints must be to prevent it from escaping. I, therefore, provide that the limiting surface shall be composed of a number of relatively narrow horizontal members, to be erected in successive rows, so that the corresponding amount of liquid may be poured back of each row as it is put in place and be allowed to cool before the next succeeding row is put in place. I also provide means for securing very tight joints both between the horizontal members and at the bottom and sides of the structure.

75 In the accompanying drawings, Figure I, is a perspective view, partly in section, of my lining apparatus in use.

Fig. II, represents a vertical section of a wall to which mastic is being applied by 80 means of my apparatus.

Fig. III, is a partial horizontal section along the line III, III, in Fig. II.

Fig. IV, is a horizontal section of a preferred form of a limiting piece to be used at 85 the corners, showing the connection with the two sides.

Fig. V, is a vertical section of a preferred form of limiting surface showing how the adjacent strips are connected.

Fig. VI, is a horizontal section along the line VI, VI, in Fig. II.

Fig. VII, shows in perspective a block used for holding in place the uppermost strip of the lining.

Fig. VIII, is a detail illustrating the adjusting means for the uprights which form the backing for the temporary limiting surface.

The upright concrete wall 1, has wire 100 cleats 2, set in it at proper intervals. This is preferably accomplished by embedding the cleat before the concrete has set. To the free ends of these wire cleats is attached a sheet of expanded metal lathing 4, or some 105 similar supporting lathing, properly spaced from the wall as by interposition of angle irons 3, as best seen in Fig. III. The limit-

ing structure is then erected at the proper distance from the wall.

In order to support the limiting surface I employ upright supporting members, comprising ladders 10, erected in substantially vertical position and at right angles to the wall or surface to be lined. These ladders are supported by braces 11, arranged so as to hold the ladders rigid and immovable. 10 Planks 12, may then be placed upon the rungs 13, to form a working platform and be moved upward as the work progresses, see Fig. II.

Upright bars 16, are adjustably secured 15 to the ladders, and find their attachment by means of a plurality of devices 17, illustrated in detail in Fig. VIII.

Each of these devices comprises a bolt 18, rigidly secured to the bar 16, and adapted to 20 be slidably received within a bushing 19, in the side rail 20, of the ladder. The bolt is of such length as to protrude a considerable distance beyond the rail 20, and threaded to receive a wing nut 21. This wing nut is 25 provided with an integral flange 22, which is held from lateral movement by a plate 23, but is capable of rotary motion therein. By this construction the bars 16, may be moved laterally with respect to the ladders 10, and 30 the front edges of these bars may thereby be accurately adjusted in parallel relation to the wall to which the plastic is to be applied, regardless of any inaccuracies in any other parts of the supporting structure. 35 The bars 16, serve as a backing for the temporary limiting surface for the plastic lining, and the spacing distance from the wall is equal to the width of this limiting surface, plus the proposed thickness of the 40 plastic lining.

The temporary limiting surface comprises limiting members preferably in the form of horizontal plates 30, which are interchangeable and formed with interfitting edges. 45 They may be of any suitable material, but preferably of sheet metal. Each plate (Fig. V) is made with a smooth limiting surface 31, and inwardly projecting upper and lower flanges 32, and 33, which form respectively 50 the upper and lower edges of the plate. The upper surface 34, of the upper flange and the lower surface 35, of the lower flange, are complementary and provided with a similar angular bend of V-shaped cross-section, so that when one plate is placed on top of another, the joint between the two will 55 be tight and snug, and the two outer surfaces 31, will lie in the same plane and form one continuous and smooth surface. The 60 flanges 22, and 23, are of such form and thickness as to admit of being clamped together by the clamps 36, which may be tightened by the thumb screw 37.

65 At each end of these horizontal plates are vertical flanges 38, 38, which extend back-

wardly from the smooth surface 31, and at right angles thereto. These flanges are so formed that abutting plates may be clamped together end to end.

Corner pieces 50, (Figs. I and IV) are 70 provided with similar flanges 51, so that they may be clamped directly to the horizontal plates 30. The outer surface 52, of the corner piece is made to conform to the shape desired for turning the corner. These 75 corner pieces need not necessarily be made the same height as the side plates. It is preferable that they should be of a greater height, since several side plates may then be secured to one end piece, resulting in 80 greater stability for the whole.

I also provide retaining blocks 60, (Fig. VIII) composed of a block 61, whose lower surface 62, is cut to engage the upper surface of the uppermost horizontal member, 85 and arms 64, extending from either side of the block 61, which are arranged to fit on either side of the bar 16, enable the block to be slid up and down the bar 16, and a thumb screw 65, by means of which the block may 90 be set in position upon the bar 16. See Fig. VI.

In operation a single course of horizontal plates 30, is first placed in position between the wall and the bar 16, extending around 95 the base line of the surface to be lined. The plates are clamped end to end, and to the corner pieces. They are then pressed tightly down against the floor or bottom, adjacent the surface to be lined, and are held in their 100 position by properly adjusted retaining blocks 60, which perform the double function of holding the plates tight against the bar 16, and also tight against the floor or bottom. This block must exert pressure 105 sufficient to form a joint so tight that none of the liquid shall be able to leak out and escape between the lower edge of the horizontal members and the bottom. The liquid is then poured in and allowed to cool and 110 set. When sufficiently set, blocks 60, are removed and another course of horizontal plates 30, placed on top of the ones already in place and clamped thereto by the clamps 36. The retaining blocks 60, are then put 115 in place on top of the new plates and the operation repeated until the entire wall is lined.

By applying the bituminous material in successive layers it will be seen that the pressure at any one point is at no time greater than that exerted by a column of liquid of height equal to the depth of the plate 30. This depth is therefore made such that the pressure exerted by a column of liquid of 125 height will not be such as to penetrate between the upper and lower flanges when pressed together by the clamps 36, and retaining blocks 60.

A lining thus constructed, provides a 130

novel, useful and practical means for applying a liquid to a vertical or inclined wall. It also has the advantage of being easily put into place, and removed, and is capable 5 of being used many times. It is also readily portable, and may be used in applying such material to structures of almost any size or height.

I have spoken of the material to be applied as bituminous, but it will be understood that my invention is applicable to other similar materials which require to be poured in a state so liquid as to be difficult of retention in position until they set.

Having thus described my invention, I claim:

1. A temporary structure of the class described comprising a series of uprights, means for holding them rigid, adjustable spacing bars supported by said uprights, horizontal limiting members supported by said adjustable spacing bars; means for holding said horizontal members against said adjustable spacing bars; and means for varying 25 the distance between the uprights and the adjustable spacing bars, said adjustable spacing bars being parallel to said uprights and arranged to support a plurality of horizontal members.

2. A temporary structure of the class described, comprising a series of uprights; means for holding them rigid; adjustable spacing bars supported by said uprights; horizontal limiting members supported by 30 said adjustable spacing bars; each spacing

bar being arranged to support a plurality of said horizontal members; means for holding said horizontal members against said adjustable spacing bars; and means for varying the distance between the uprights and 40 the adjustable spacing bars.

3. In a temporary structure of the class described, the combination of horizontal limiting members; an adjustable spacing bar adapted to support a plurality of said 45 limiting members; a rigid upright supporting said adjustable spacing bar; and means for varying the distance between the upright and the spacing bar.

4. In a temporary structure of the class described, the combination of a plurality of horizontal limiting members; an adjustable spacing bar supporting said limiting members; a rigid upright supporting said adjustable spacing bar; and means for varying 50 the distance between the upright and the spacing bar, including a bushing in said upright, a bolt rigidly secured to said spacing bar, adapted to slide within said bushing, and to protrude beyond said bushing, 55 and a flanged nut adapted to engage the end of said bolt.

In testimony whereof, I have hereunto signed my name at Philadelphia, Pennsylvania, this thirtieth day of December, 1914. 60 65

HENRY WIEDERHOLD.

Witnesses:

JAMES H. BELL,
E. L. FULLERTON.
